UNITED STATES PATENT OFFICE.

EMMIT G. LATTA, OF FRIENDSHIP, NEW YORK, ASSIGNOR OF ONE-HALF
TO HARVEY A. MOYER, OF SYRACUSE, NEW YORK.

LINE-SPACING AND CARRIAGE-RELEASING MECHANISM FOR TYPE-WRITING MACHINES.

No. 822,210.

Specification of Letters Patent.

Patented May 29, 1906.

Original application filed August 4, 1903, Serial No. 168,190. Divided and this application filed May 14, 1904. Serial No. 208,011.

To all whom it may concern:

Be it known that I, EMMIT G. LATTA, a citizen of the United States, residing at Friendship, in the county of Allegany and State of New York, have invented new and useful Improvements in Line-Spacing and Carriage-Releasing Mechanism for Type-Writing Machines, of which the following is a specification.

This invention relates to line-spacing or paper-feeding and carriage-releasing mechanism for type-writing machines, and is more particularly directed to improvements in visible writing-machines of that kind in which the type-bars are pivoted below the platen and swing upwardly and rearwardly to make the impression at the front side of the platen where the writing can be seen by the operator without moving the carriage or platen. Such a machine is disclosed in my application for United States Letters Patent, Serial No. 168,190, filed August 4, 1903, of which the present application is a division. The improvements are, however, also applicable to other forms of type-writing machines.

One object of the invention is to provide a simple and desirable mechanism for releasing the carriage-escapement to permit the carriage to be shifted manually and for turning the platen to feed the paper or produce the line-spacing.

Another object of the invention is to so construct the line-spacing mechanism that a part thereof also serves to actuate the ribbon-feed device to move the ribbon upon each actuation of the line-spacing mechanism.

In the accompanying drawings, consisting of two sheets, Figure 1 is a transverse sectional elevation of a portion of a type-writing machine provided with line-spacing and ribbon-feeding mechanism embodying the invention. Fig. 2 is a plan view thereof. Fig. 3 is a longitudinal sectional elevation thereof, showing the normal position of the platen. Fig. 4 is a similar view showing the platen and carriage lowered for printing upper-case characters. Fig. 5 is an end elevation of the carriage and its bearing. Fig. 6 is a horizontal section of the bearing for one of the line-space levers in line 66, Fig. 5.

Like letters of reference refer to like parts in the several figures.

A represents the platen, which, as usual, has a shaft *a*, journaled to rotate on a carriage, which is movable laterally or cross-wise of the machine on a stationary horizontal rail or track *B*, Figs. 3, 5, which extends across and is supported by the rear portion of the main frame *b*.

C, Fig. 3, represents one of the type-bars, which are pivoted below and in front of the platen on a curved segment *c* in such position as to make the impression at the front side of the platen.

The carriage shown in the drawings consists of two end pieces or bars *D* and front and rear transverse horizontal connecting rods or bars *d d'*. The rear bar passes loosely through bearing-brackets *d²*, Figs. 2, 3, and 5, secured by screws or otherwise to ears *d³*, projecting rearwardly from the end portions of a bearing-bar *e*, which is supported by and slides on the stationary track *B*. The machine shown is of that kind in which each type-bar is provided with two characters, commonly called "upper and lower case characters," and the carriage is capable of being shifted downwardly from its normal position (shown in Fig. 3) to the position shown in Fig. 4 to properly place the printing-point to be engaged by the upper-case type. For this purpose the rear transverse rod of the carriage is allowed to turn in its supporting-bearings. The carriage is held up in its normal position by springs *f*, Fig. 2, coiled about the rear bar of the carriage and connected at their opposite ends, respectively, to said bar and to the bearing-brackets therefor in any suitable manner. The springs permit the carriage to be moved downwardly by a shifting device (not shown) and return it to the normal position when released. The carriage may be constructed, and supported in any other suitable manner.

The platen is turned to feed the paper and produce ordinary line-spaces by the following mechanism: *G*, Figs. 1, 2, and 5, represents a ratchet wheel or plate secured in any suitable manner to one end of the platen, preferably the right end, and having ratchet-teeth *g* near its outer edge. *H*, Figs. 1 and 2, represents the regular line-space or paper-feed lever for turning the platen. The lever is located at the right end of the carriage and has a rearward extension passing under the

platenshaft and provided with two fixed or integral arms h , which are pivoted to lugs h' , projecting from the adjacent side piece of the carriage by a screw or pin h^2 . h^3 is a spring which surrounds the pivot-pin h^2 and is connected at its ends to the side piece of the carriage and line-space lever and acts to retain the lever in its normal position. The line-space lever is provided at its front end with an arm which projects toward the ratchet-plate and carries a pivoted pawl I, Fig. 1, the upper free end of which is adapted to engage with the ratchet-teeth to turn the platen. The pawl I is provided with a depending arm or portion i , which rests in the normal position of the lever on the adjacent portion of the front transverse rod d of the carriage and acts as a stop for the lever and also to hold the pawl out of engagement with the teeth of the ratchet-plate. When the lever is operated, the first portion of its movement lifts the pawl off of the carriage-rod, and its free end falls into engagement with one of the teeth of the ratchet-plate, which latter is turned by the further movement of the lever. The extent of rotary movement of the ratchet-plate and platen is determined by any suitable adjustable stop. For this purpose a curved lever i' is shown, which is pivoted on the end piece D of the carriage in rear of the platen-shaft and is provided at its front end with a tooth or projection i^2 , adapted to spring into either of two or more recesses in the end piece of the carriage to hold the lever in different stop positions. The platen can be held against rearward rotation by any usual means. K, Figs. 1 to 4, represents a lever similar to the line-space lever H, arranged at the opposite end of the carriage and similarly pivoted thereto by a suitable screw or pin k . L, Figs. 1, 3, and 4, is a bar of angular shape in cross-section which is arranged longitudinally beneath the platen and is provided with upturned ends l , which are pivoted to arms $m m'$ on the line-space levers H K, respectively. This bar connects the two levers so that when the lever K at the left end of the carriage is operated power is transmitted therefrom to the other lever H at the right end of the carriage, and the platen is turned by the pawl and ratchet-plate, as above described. The two line-space levers and their connecting-rods thus afford means for turning the platen from either end thereof. The connecting-rod L also constitutes the means for releasing the carriage feed or escapement and actuating the ribbon-feed device, as hereinafter explained.

O, Figs. 1, 3, and 4, represents a carriage-driving drum or barrel of any suitable construction which is journaled at the rear of the machine beneath the carriage-supporting track B on a stud or axle projecting from the rear portion of the main frame. The drum is

driven by an inclosed spiral spring p , connected thereto and to the drum-axle, and is provided with gear-teeth p' , which mesh with rack-teeth p'' on the sliding bearing-bar of the carriage. The spring-drum tends to turn to the left and move the carriage to the left, as usual, and is controlled or operated to move the carriage step by step to produce the letter-spacing by escapement mechanism p^2 , which is fully described in my said application.

Q, Figs. 3 and 4, represents a carriage-release lever, which together with a ribbon-feed lever q , is pivoted on a bracket q' , secured to the carriage-track, and extending forwardly beneath the platen. The release-lever is arranged with its free end beneath the free end of the ribbon-feed lever, which in turn is beneath the horizontal bar L, connecting the line-space levers H K, so that when said bar is depressed by the operation of either of the line-space levers the ribbon-feed lever q is depressed and striking the release-lever Q depresses the latter. The carriage-release lever is connected to the upper end of a rod q^2 , the lower end of which has a rearward extension which projects over the arm of the escapement-pawl q^3 .

The actuation of either line-space lever operates through the ribbon-feed lever, release-lever, and rod q^2 to disengage the escapement-pawl from the ratchet-wheel, thereby avoiding the noise and wear of the parts of the carriage-escapement when the platen is turned and the carriage set back for a new line. The parts are so adjusted that a slight movement of either line-space lever will release the escapement-pawl and free the carriage, and a further movement of the lever will turn the platen and move the ribbon-feed lever to feed the ribbon, which is shown at R, as explained in my application for the ribbon mechanism, Serial No. 196,282, filed March 3, 1904. The cross-sectional shape of the bar L, connecting the line-space levers, is such that when the platen is in the normal position for printing lower-case characters its rear edge strikes and operates the ribbon-feed lever q , and when the carriage is lowered to print upper-case characters, as shown in Fig. 4, the bar is moved downwardly and rearwardly, with its front edge or a rib thereon above the ribbon-feed lever in position to actuate the same.

I claim as my invention—

1. In a type-writing machine, the combination of a carriage, an escapement therefor, a rotatable platen and platen-shaft on said carriage, a toothed wheel at one end of said platen; a lever adjacent to said toothed wheel having an upright operating-arm located in front of the platen-shaft, and a pivot extension projecting rearwardly under the platen-shaft and pivoted to the carriage, a pawl on

said lever acting to engage said toothed wheel and turn the platen when said operating-arm is moved, and a carriage-releasing device connected to the rear portion of the pivot extension of said lever, substantially as set forth.

5 2. In a type-writing machine, the combination of a rotatable platen, a laterally-movable carriage for the same, a pair of finger-levers pivoted to the carriage to swing in line with the carriage movement, a connecting-rod arranged below the platen by which the levers are caused to move together, and connections between one of the levers and the platen whereby the movement of either lever in the direction of the carriage travel acts to both rotate the platen and set the carriage back for a new line, substantially as set forth.

15 3. In a type-writing machine, the combination of a rotatable platen, and a platen-shaft, a supporting-carriage for the same, a pair of upright finger-levers at the ends of the platen and in front of the platen-shaft, said levers having pivotal extensions arranged under the platen-shaft and having arms in rear of the same, a rod connecting said arms, and connections between one of the levers and the platen whereby the latter is rotated by the movement of either of the levers, substantially as set forth.

25 4. In a type-writing machine, the combination of a rotatable platen, and a platen-shaft, a supporting-carriage for the same, a pair of levers pivoted to the carriage at the ends of the platen and having pendent arms in rear of the platen-shaft, a rod arranged beneath the platen and connecting said arms whereby the movement of either lever is transmitted to the other lever, and connections between one of said levers and the platen for turning the latter, substantially as set forth.

35 5. In a type-writing machine, the combination of a rotatable platen, and a carriage for the same, a step-by-step escapement for the carriage, a lever at each end of the platen for turning the latter, a connecting-rod between the levers, and a connection between the rod and the escapement acting to release the carriage when either lever is turned, substantially as set forth.

45 6. In a type-writing machine, the combination of a rotatable platen, a carriage for the same, a step-by-step movement for the carriage, a lever at each end of the platen for turning the latter, and a connecting-rod between the levers which acts to release the carriage-escapement upon the movement of

either of the levers before the platen is turned, substantially as set forth.

5 7. In a type-writing machine, the combination of a rotatable platen, a carriage for the same, a step-by-step escapement for the carriage, a lever at each end of the platen for turning the platen, and a rod connecting the levers and acting to release the carriage-escapement with a limited movement of either lever prior to the movement of the platen, a further movement of either one of the levers acting to turn the platen, substantially as set forth.

15 8. The combination of a rotatable platen, a supporting-carriage therefor which is shifted vertically to change the position of its printing-point, levers at opposite ends of the carriage for turning the platen, a rod connecting said levers, a carriage-escapement, and a release-lever therefor which is actuated by said connecting-rod in the different positions of the carriage, substantially as set forth.

25 9. The combination of a rotatable platen, a supporting-carriage therefor, levers at opposite ends of the carriage for turning the platen, a rod connecting said levers, a carriage-escapement, and a release-lever therefor which is fulcrumed in fixed relation adjacent to said connecting-bar and is actuated thereby, substantially as set forth.

35 10. The combination of a rotatable platen, a supporting-carriage therefor, levers at opposite ends of the carriage for turning the platen, a rod connecting said levers, a carriage-escapement, a release-lever therefor, and a ribbon-feed lever both of which levers are actuated by said connecting-rod, substantially as set forth.

45 11. The combination of a rotatable platen, a supporting-carriage therefor, line-space levers at opposite ends of the carriage for turning the platen, a rod connecting said levers, a carriage-escapement, a release-lever therefor, and a ribbon-feed lever both of which levers are actuated by said connecting-rod, the parts being so arranged and adjusted that said line-space levers can be actuated to first release the carriage-escapement and thereafter actuate the ribbon-feed lever and turn the platen, substantially as set forth.

55 Witness my hand this 5th day of May, 1904.
